CLAIM

The ornamental design for a “paper case of a camera,” as shown and described.

DESCRIPTION

FIG. 1 is a top perspective view of a paper case of a camera showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, showing the paper case of a camera in use.

The broken lines depict portions of the paper case of a camera which form no part of the claimed design.
